APPARATUS FOR SECURING FASTENING ELEMENTS TO FUR GARMENTS

Arthur A. Littman, Milwaukee, Wis.

Application September 15, 1951, Serial No. 246,773

2 Claims. (Cl. 1-4)

1

My invention appertains to fur garment making and more particularly to an apparatus for securing fastening elements thereto.

A salient feature of my invention is to provide a special type of hook and eye and an improved machine for securing the hooks and eyes to a fur garment in accordance with the method disclosed in my co-pending application filed August 17, 1951 for a Method and Apparatus for Affixing Fastening Elements to Fur Garments, Serial Number 242,206.

Briefly, this method which is more fully disclosed in my co-pending application relates to a new and novel means of applying the hooks and more particularly the eyes to a finished fur garment without the necessity of slitting the fur or removing the garment lining.

One of the primary objects of the present invention is to provide a newly designed eye element which is an improvement over the eye shown and described in my co-pending application.

A further object of my invention is to provide an improved eye element in which the shank portion of the eye lies parallel to the eye loop and will overlie the fur to protect the same when the sharp prong terminals are securely fastened to the hide; whereby the hook element received in the eye loop will not come in contact with the fur.

Another important object of my invention is to provide a specific type of machine which is an improvement over the machine shown and described in my co-pending application, and which is adapted to selectively receive and hold the hook and my improved eye element firmly in the desired position.

Still another object of my invention is to provide the head of my machine with a pivoted holding and straightening member which, upon actuation of the machine, will tend to straighten and correct any deformities in the hook or eye held therein.

A more specific object of my invention is to provide the base portion of my machine with a modified interchangeable anvil member so that the machine may be used where the eye is to be placed close to the edge and between the edge folds of the garment.

A still further object of my invention is to provide a simple, practical and reliable construction that is economical to manufacture, easy to assemble and positive in its operation.

With these and other objects in view, the invention consists in the novel construction, arrangement and formation of parts, as will be hereinafter more specifically described, claimed.

2

and illustrated in the accompanying drawings, in which drawings:

Figure 1 is a side elevational view of my improved machine for affixing the hooks and eyes to the hide, parts of the base and anvil member being broken away to illustrate certain details of construction;

Figure 2 is a top plan view partly in section, of my machine, and illustrating more particularly the hinge structure for the holding and straightening member, the section being taken on the line 2-2 of Figure 1, and looking in the direction of the arrows;

Figure 3 is a fragmentary top plan view, partly in section, of the top surface of the support and driving member of my machine, and illustrating the novel means for selectively holding either a hook or eye element, the section being taken on the line 3-3 of Figure 1, and looking in the direction of the arrows;

Figure 4 is a vertical section through the support and driving member of my machine and illustrating further details of construction of the hinge, the section being taken on the line 4-4 of Figure 1 and looking in the direction of the arrows;

Figure 5 is a fragmentary top plan view of the base and anvil member of my machine;

Figure 6 is a perspective view of the hook element used in accordance with the present invention;

Figure 7 is a fragmentary side elevational view of the support and driving member of my machine, partly in section, and illustrating in particular how the hook element is held in the proper position;

Figure 8 is a longitudinal section through the head portion of my machine, the section being taken on the line 8-8 of Figure 7, and looking in the direction of the arrows;

Figure 9 is a fragmentary bottom plan view of the head portion of my machine, a section being taken through the hook element on the line 9-9 of Figure 7, and looking in the direction of the arrows;

Figure 10 is a fragmentary side elevational view, partly in section, illustrating a step necessary in affixing the hook element to the fur garment;

Figure 11 is a perspective view of my new and improved eye element;

Figure 12 is a side elevational view similar to Figure 10 of the drawings, but showing in particular how my new and novel eye element is held in the machine;

Figure 13 is a longitudinal section through the

head of my machine, similar to Figure 8 of the drawing, but illustrating the eye element held therein, the section being taken on the line 13—13 of Figure 12, and looking in the direction of the arrows:

Figure 14 is a fragmentary bottom plan view of the head and hammer of my machine showing the eye element held therein, the section being taken on the line 14—14 of Figure 12, and looking in the direction of the arrows;

Figure 15 is a fragmentary side elevational view partly in section, of a modified form of anvil member, and illustrating how the modified form may be secured to the base of my machine;

Figure 16 is a perspective view of the eye element similar to Figure 11 of the drawing, but illustrating a modified form in the shank of the eye element;

Figure 17 is a similar perspective, but illustrating a further modification of the shank of my eye element.

Referring to the drawings in detail, wherein similar reference characters designate corresponding parts throughout the several views, the letter A generally indicates my novel machine which is utilized to affix the fastening elements to the fur garments, and which is an improvement over the machine shown and described in my co-pending application.

In the preferred embodiment of the machine A, I form the base member 10 and support and driving member 11 of a single strip of spring metal 12. The spring metal 12 is U-shaped in construction and consists primarily of an upper stretch 13 and a lower base stretch 14. The lower base stretch 14 is formed as a narrow thin tongue and has detachably secured thereto the anvil member 15. The anvil member 15 may be detachably secured to the lower stretch 14 by any desired means. However, as shown, the stretch 14 and thin length 16 are overlapped and secured by set screw 17.

The support and driving member 11 is provided on its under surface with a longitudinally extending projection 18, the purpose of which will become apparent as the description proceeds. On the upper surface of the support and driving member 11, I form a longitudinally extending recess 19. The indentation or recess 19 (Figure 3) is provided with a large arcuate portion 20 and a centrally disposed smaller arcuate shaped portion 21. As will be readily seen, the smaller arcuate portion 21 receives the upper portion of the hook H while the larger indentation 20 receives the eye loop of the eye element E (Figure 11).

Pivotedly secured adjacent the rear termination of the indentation 21 by means of a pivot rod 22 extending through upstanding ears 23 and 24 of the support and driving member 11 is a holding and straightening member 25 on the upper surface of which is formed the actuating knob K of the machine. The member 25 also has formed integral with its forward surface a downwardly extending projection 26 which terminates adjacent the bottom surface of the support and driving member 11. This projection is also spaced from the forward surface of the support and driving member 11 forming an opening or slot 27. This slot 27 is just wide enough to allow the respective portions of the hooks and eyes to extend downwardly therethrough. Any deformation or unintended bend in the respective portions of the hooks or eyes will likewise

be corrected when pressure is exerted on the member 25.

The anvil member 15 which lies directly under the support and driving member 11 is enlarged somewhat to receive two parallel recesses 28 which will be later more fully described.

Referring now to Figure 6 of the drawings, it can be seen that the hook H which is utilized in practicing the method disclosed in my co-pending application is similar to the hook shown and described therein, and is formed from a single piece of heavy gauge wire bent to form a hook portion 29 and a shank portion 30.

The shank 30 is formed by two parallel stretches 31 which are carried outward and parallel to the hook portion 29 and thence at right angles to the shank to form sharp prong terminals 32. While it is not necessary, the prong terminals 32 may be roughened or notched at 33 in order to provide a better grip on the under portion of the hide.

When it is desired to affix the hook H to the edge fold 34 of the fur garment G, the holding element 25 is lifted on its pivot 22 to its dotted line position in Figure 1, and the hook portion 29 of the hook H is laid on the top surface of the support and driving member 11 in the smaller arcuate portion 21 of the recess 19 as illustrated in Figure 8 of the drawing. The member 25 is then pivoted downwardly to its full line position and the hook is held firmly to the hammer 11, and also by exerting pressure on the knob K any unnecessary bends or deformities in the hook H will be immediately straightened. It is also to be noted that the parallel members 31 of the hook shank 30 extend on either side of the projection 13 to prevent any lateral movement of the lower portion of the hook H.

Referring now in particular to Figure 10 of the drawings, it can be seen that when pressure is exerted upon the knob K, the sharp prong terminals 32 of the hook H will penetrate the hide 34 to be guided by the recesses 28 of the anvil 15 and turned upwardly and back into the under portion of the hide. The hook will then be firmly clinched and embedded in the edge fold 34 of the garment G as shown.

In Figure 11 of the drawings, I have illustrated the preferred form of my improved eye member, and it is to be noted that the eye E is also constructed from a single length of heavy gauge wire bent to form an eye loop 35, a shank portion 36 and the sharp prong terminals 37. It is to be noted that the shank portion 36 is substantially parallel to the eye loop 35, and that the wire stretches forming the shank 36 may be bent inwardly to provide parallel extending stretches 38 which lie in the same plane as the laterally extending stretches 39 of the shank. Stretches 38 and 39 of the shank 36 cooperate to form a protecting element which overlies the fur of the garment G and protects the same from undue wear, will not permit the hook portion 29 to contact the fur, and cooperates with the prongs 37 to keep them from pulling out of the hide. Prongs 37, of course, are parallel and extend downwardly at right angles from the stretches 38. It is also to be noted that the shank 30 of the hook H likewise prevents the eye loop 35 from contacting and wearing the fur. The hook H and eye E may be covered with a suitable fabric F which is designed to conform with the color and texture of the fur garment.

Figures 12, 13 and 14 illustrate the manner in

which the eye is held to the head or support and driving member portion 11 of my machine. Figure 13 shows the eye loop 35 conforming to and received in the large arcuate portion 20 of the recess 19. Again it is to be noted that the holding member 25 will straighten out any defects in curvature or shape of the eye loop when pressure is exerted thereon. In affixing the eye element E to the outside hide 40 of the fur garment G, its position must first be determined by fitting the garment to the wearer or purchaser. After its position has been properly determined, the eye E is placed in the recess 19 on the top surface of the support and driving member 11 of the machine in the position illustrated, and pressure is again exerted on the knob K. This will drive the sharp prong terminals 37 through the hide from the fur side, and by means of the recesses 28 in the anvil 15 turn the prongs upward and back into the under side of the hide 40, it being understood that the thin base 10 and anvil member 15 is slipped between the stitches of the fur hide and lining, as more fully shown and described in my co-pending application.

Figures 16 and 17 illustrate modifications in the shank 36 of my novel eye E, and in Figure 16 the shank 36' is formed by turning the stretches 38' to the outside of the stretches 39' instead of inwardly as illustrated in Figure 11.

Figure 17 illustrates a further modification in which one of the stretches 38'' of the shank 36'' is turned inwardly and the other stretch 38'' is turned outwardly with respect to the stretches 39''.

Figure 15 discloses a modified form of anvil similar to that disclosed in Figure 18 of my co-pending application and this form of anvil member is particularly suited for securing the eye E to the outer edge of the garment between the edge fold of the hide, which necessitates slipping the base 14 between the lining and the edge fold and then drawing rearwardly to slip the anvil 15' between the two folds of the fur. The anvil 15' is also formed with parallel recesses 28' which function similarly to the recesses 28, and the stretch 16' is secured to the lower base stretch 14 of my machine by means of the same set screw 17.

From the foregoing, it is believed that the features and advantages of my invention will be readily apparent to those skilled in the art, and

it will, of course, be understood that changes in the form, proportion and minor details of construction may be resorted to without departing from the spirit of the invention or the scope of the appended claims.

I claim:

1. An apparatus for affixing hooks and eyes of the type having sharp prong terminals to fur garments comprising, a U-shaped body formed from a single length of spring metal, an anvil member secured to the outer end of one stretch of said body, said anvil member being of a size and configuration to be inserted between the lines of stitching of said fur garment, a support and driving member formed on the outer end of the other stretch of said body for cooperation with said anvil member, a longitudinally extending projection on the under surface of said support and driving member, and means including a recess formed in the upper surface of said hammer member of a size and configuration to selectively receive and hold either a hook or eye.
2. An apparatus for affixing hooks and eyes of the type having sharp prong terminals to fur garments comprising a U-shaped body formed from a single length of spring metal, an anvil member detachably secured to the outer end of the lower stretch of said body, a support and driving member formed on the outer end of the upper stretch of said body for cooperation with said anvil member, a longitudinally extending recess formed in the upper surface of said support and driving member, said recess including a large arcuate portion and a smaller centrally disposed arcuate portion, and a holding and straightening member pivotally secured above and adjacent the rear termination of said recess, whereby any unnatural deformation in the hook or eye held therein will be pressed and straightened.
